ROTARY VEGETABLE CUTTER

John J. Lee, Wilmington, Calif.

Application May 17, 1937, Serial No. 143,047

2 Claims. (Cl. 146—89)

This invention relates to a rapid means for cutting vegetables and the like into small particles.

More specifically stated, the invention pertains to a superior means for rotatably supporting a multiplicity of small cutting elements upon a drum or the like and in such a relation to a feed passage and abutment that a device is produced which will rapidly convert an edible object, for example a cabbage head or carrot, into a finely divided condition, such as has hitherto been possible only by much slower and more laborious means to operate.

One object of the invention is to provide a superior toothed cutting blade whereby a multiplicity of cutting teeth may be manufactured at a lower cost and assembled in a more advantageous manner.

Other objects, advantages and features of the invention may hereinafter appear.

Referring to the accompanying drawing which illustrates what is at present deemed to be a preferred embodiment of the invention,

Fig. 1 is a vertical section of the device on line 1—1 of Fig. 2.

Fig. 2 is a side elevation thereof with a portion of the casing broken away in order to disclose interior construction, the section taken on line 2—2 of Fig. 1.

Fig. 3 is a fragmental elevational view of one of the cutting elements.

Fig. 4 is a sectional view taken on line 4—4 of Fig. 2.

Referring in detail to the drawing, a combined standard and gear casing 10 is shown furnished with a mounting means 11 carrying a clamping screw 12 whereby the device may be detachably secured to a table top 13. Said casing 10 is furnished in its central portion with an outwardly directed bearing extension 14 which supports the shaft 15 of the crank 16 which is secured to the outer end of said shaft, while to its inner end is secured the driving gear 17. Said gear meshes with a pinion gear 18 secured to a shaft 19 supported by the upper bearings 20 and 21.

To the inner end of the pinion shaft 19 is secured the circular cutter head 23 which carries a sleeve or tubular member 24 having an end portion 25. The head 23 may be made of wood or metal, and if made of metal may be integral with the tubular member 24, or as shown, said member 24 may be of a cup-shaped character and the head 23 fitted into its bottom portion to stiffen and strengthen it. The shaft 19 has fixed to it an inner collar 27 and the means for securing the rotary cutter to the shaft 19 is completed

by means of a sleeve 28, fitted within a central opening therefor in said head 23 and cooperating with a washer 29 and securing nut 30.

The tubular part 24 has exteriorly secured to it a plurality of substantially parallel spiral blades 33, each of these blades having deep serrations 34 along its outer edge, thus forming the intervening cutter teeth 35. Said teeth are inclined backwardly with respect to the clock-wise direction of rotation of the crank required to operate the device properly.

The rotary cutter assembly which has been described is housed axially within a cylindrical casing 40 having a radially extending feeding extension 41 which is located at one side rather than in the top of said casing. In the lower portion of said extension and at its inner end is an abutment or shoulder 42 which supports substances being fed to the cutter and holds such substances up against the cutters in such a way that a rather rapid rotation of the cutter assembly in the proper direction will rapidly cut vegetables such as carrots, cabbages, etc., into small fragments. Said casing 40, as shown, is somewhat drum shaped, but it has an open lower side with downwardly directed lateral skirt portions 43 and also has an end opening or recess 44. The latter opening permits the operator more readily to inspect the product delivered by the machine to the receptacle 45 which is shown disposed under the open side of the casing 40.

The feeding extension 41 is of a flattened character, the width of its throat being considerably greater than its vertical extent. Its lower side is longer than its upper side, thus producing a rest or lip 41a to aid in feeding materials to the cutters.

In the lower part of said extension 41 is a presser plate 41b having its outer end highest and supported by a pivot member 41c which extends through the side portions of the extension 41. Its inner end is upturned at 41d. Compression springs 41s bear against the upper side of this pivoted plate to cause it to engage the fed materials with a moderate pressure and thereby keep in a somewhat compact condition, any leafy vegetable or like substances being fed under said plate 41b to the cutters. The lower wall or bottom of the extension 41 is furnished with corrugations 41x and the presser plate 41b is likewise furnished with corrugations 41z, these corrugations all running in the direction which the fed materials move. Said extension bottom and presser plate are positioned to grip the fed materials between their corrugated portions. There-

fore said corrugations all cooperate to prevent a side-to-side shifting of the materials being fed to the machine and are particularly valuable in view of the fact that the spirally arranged cutters would otherwise tend to shift the fed mass towards one side of the feed passage.

From Fig. 4 it is to be seen that the corrugations **41x** and **41z** are so arranged in relation to each other that they will interfit when the lower end of the member **41b** (Fig. 2) is pressed into contact with the corrugations of the floor of the inclined feeding extension **41**. Hence plant or vegetable stems having a small cross-section cannot slide in a lengthwise manner down the feeding extension between the corrugations without being gripped and held with a suitable firmness while being acted upon by the cutters.

As the vegetables or other substances to be cut into fine pieces are fed through the passage within the extension **41**, the crank **16** is turned in a right hand, or clockwise, direction thus rotating the cutter assembly in a left hand, or anticlockwise, direction and causing the cutting teeth to move downwardly as they pass by the abutment **42** at the inner end of the feed passage.

Hence the inwardly projecting portion of the vegetable being fed into said casing as aforesaid is rapidly cut by a slicing action into small pieces a stream of which falls into the receptacle **45**. The best results are obtained when the abutment **42** is located somewhat below the midheight of the rotary cutter assembly and the feed passage is also inclined somewhat downwardly. One of the novel features of the invention resides in the relation of the feeding means to the rotary cutter assembly specified.

The points of the teeth **35** are inclined in such a way as to be directed backwardly, in relation to the direction of rotation of said teeth **35**, adjacent to the abutment **42**, thus giving them a superior capacity for cutting and clearing themselves from the cut materials.

I claim:

1. A cutting mechanism of the kind described

including a casing, an extension leading downwardly into said casing, said extension having a bottom portion corrugated in the direction which the fed materials move, a presser plate pivotally mounted upon said extension in an upwardly spaced relation to its corrugated floor portion, said presser plate having downwardly directed corrugations extending in the same direction as the corrugations of said extension, springs tending to swing said presser plate downwardly against the materials being fed, and cutting means comprising a rotatable drum having spiral cutting means thereon within said casing rotatable in a direction tending to move the fed materials downwardly through said extension, the cutters of said cutting means also tending to shift the fed materials laterally in opposition to the action of the cooperating corrugated means aforementioned.

2. A cutting mechanism of the kind described including a casing, an extension leading downwardly into said casing, said extension having a bottom portion corrugated in the direction which the fed materials move, a presser plate pivotally mounted upon said extension in an upwardly spaced relation to its corrugated floor portion, said presser plate having downwardly directed corrugations extending in the same direction as the corrugations of said extension, springs tending to swing said presser plate downwardly against the materials being fed, and cutting means comprising a rotatable drum having spiral cutting means thereon within said casing rotatable in a direction tending to move the fed materials downwardly through said extension, the cutters of said cutting means also tending to shift the fed materials laterally in opposition to the action of the cooperating corrugated means aforementioned, portions of said cooperating corrugated means having opposed corrugations positioned to interfit with each other and make a close gripping contact upon vegetable substances having a small cross-section.

JOHN J. LEE.
